[57] CLAIM

The ornamental design for a fiber-optic cable, as shown.

DESCRIPTION

FIG. 1 is an isometric view from the front of a fiber-optic cable incorporating our design;
FIG. 2 is a left-side view thereof;
FIG. 3 is a front view thereof;
FIG. 4 is a bottom view thereof;
FIG. 5 is a back view thereof;
FIG. 6 is a right-side view thereof; and,
FIG. 7 is a top plan view thereof with the cable broken to indicate that the specific cable length is arbitrary.
